UNITED STATES PATENT OFFICE.

GEORGE R. HOWEY, OF PHILADELPHIA, PENNSYLVANIA.

NON-REFILLABLE BOTTLE.

No. 824,018.

Specification of Letters Patent.

Patented June 19, 1906.

Application filed October 19, 1905. Serial No. 283,364.

To all whom it may concern:

Be it known that I, GEORGE R. HOWEY, a citizen of the United States, residing at Philadelphia, county of Philadelphia, and State of Pennsylvania, have invented a certain new and useful Improvement in Non-Refillable Bottles, of which the following is a specification.

My invention relates to a new and useful improvement in non-refillable bottles, and has for its object to provide a simple and effective construction that will entirely overcome the defects which have heretofore existed in such bottles, thus effectively preventing the refilling of a bottle after its contents have been drawn therefrom, thus enabling the proprietor of various brands of liquids—such as whisky, cologne, and the like—to put their goods upon the market with the assurance that the bottles will not be refilled with a cheaper grade of material, which would naturally tend to injure the reputation of the proprietor of a particular brand of goods and also deceive the purchaser.

With these ends in view my invention consists in the details of construction and combination of elements hereinafter set forth and then specifically designated by the claims. In order that those skilled in the art to which my invention appertains may understand how to make and use the same, I will describe its construction in detail, referring by letter to the accompanying drawings, forming a part of this specification, in which—

Figure 1 represents a bottle made in accordance with my improvement; Fig. 2, a section of a portion thereof; Fig. 3, a detail section of the cap before it is crimped on the bottle, and Fig. 4 a detail perspective of the valve.

Referring to the drawings, A represents a bottle, the body of which may be of any ordinary construction, the neck B of which is flared upward and outward, so as to form a funnel-shaped mouth of any desired height. Within this neck is located a valve C, preferably of glass, said valve being adapted to fit the inner inclined walls of the neck and when seated to prevent the inward flow of liquid. I prefer that this valve shall have a cup-shaped recess D formed in the upper side thereof for the purpose hereinafter set forth.

E represents the cap, which is preferably made of sheet metal, and when fitted to the

neck of the bottle the flanges thereof are crimped or spun under the flared edges of the neck, so as to firmly hold it in place. This cap has a tube F projecting upward therefrom, which serves as the mouth of the completed bottle and is adapted to receive a cork G, by which the bottle is closed, as will be readily understood. Lugs H project outward from the under side of the cap in order that when the bottle is inclined for pouring the contents therefrom the valve striking against these projections will not obstruct the outward flow of the liquid.

From the foregoing description it will be seen that in filling bottles made in accordance with my improvement the liquid is poured into the same in the usual manner prior to the cap or valve being placed in position, after which the valve is dropped into its seat and the cap, which will then be in the shape shown in Fig. 3, placed over the mouth of the bottle and its depending sides E' crimped under the edges of the outwardly-flared neck, thus securely holding it in place and at the same time sealing it to said neck. For this purpose any suitable hand or power crimping machine may be used for turning the sides of the cap under the flared edges of the neck of the bottle.

When it is desired to withdraw the contents or any portion thereof from the bottle, it is tilted in the usual manner, and the valve by gravity will drop from its seat and the liquid be permitted to flow around the valve and out of the tube F, from which the cork G has previously been withdrawn; but as soon as the bottle is returned to its normal upright position the valve will again be seated. When the valve is in this position, any attempt to fill the bottle through the tube F will increase the weight of the valve by the liquid flowing into the recess D, thus firmly seating said valve, and should an attempt be made to refill the bottle by inverting and immersing it in a quantity of liquid the first action of any liquid flowing upward through the tube F will be to float the valve upward against its seat, and the air accumulated in the then-inverted recess D will assist in holding the valve tightly upon its seat.

Having thus fully described my invention, what I claim as new and useful is—

1. In combination with a bottle, a neck formed therewith, said neck being flared upward and outward, a cap, the sides of which are crimped under the flared edges of the

28
neck, a tube formed with the cap serving as an outlet for the contents of the bottle and adapted to receive a cork for closing the bottle, a valve having a recess formed in its upper side, said valve adapted to fit the inner walls of the flared neck to prevent the passage of liquid to the bottle, and lugs projecting outward from the under surface of the cap so as to prevent the valve from obstructing the outward flow of the contents of the bottle, as specified.

2. In combination with the flared neck of a bottle, a valve adapted to fit the inner walls of said neck, said valve having a recess formed

therein, a cap fitted to the mouth of said neck 15 and having its sides crimped under the flared edge of the neck so as to secure it in place, said cap having a tube projecting upward therefrom for the outward flow of the liquid, as specified.

20
In testimony whereof I hereunto affix my signature in the presence of two subscribing witnesses.

GEORGE R. HOWEY.
